UNITED STATES PATENT OFFICE.

HARRY A. MILLER, OF LOS ANGELES, CALIFORNIA, ASSIGNOR, BY MESNE ASSIGNMENTS, TO MASTER CARBURETER COMPANY, OF LOS ANGELES, CALIFORNIA, A CORPORATION OF CALIFORNIA.

CARBURETER.

1,183,222.

Specification of Letters Patent. Patented May 16, 1916.

Application filed May 20, 1914. Serial No. 839,732.

To all whom it may concern:

Be it known that I, HARRY A. MILLER, a citizen of the United States, residing at Los Angeles, in the county of Los Angeles and 5 State of California, have invented a new and useful Carbureter, of which the following is a specification.

An object of this invention is to improve the construction of carbureters of the character disclosed in the prior application of 10 Harry A. Miller and Frank M. Adamson, filed February 10, 1914, Serial No. 817,779.

The distributor of the carbureter which is located adjacent to the throttle is provided 15 with a series of ducts or small passages, the discharge mouths of which are controlled by the throttle so that by adjusting the angular position of the throttle more or less of the discharge ducts of the distributor may be 20 opened for the passage of gasolene.

A further object of the invention is to provide for conducting gasolene to these several passages and to also provide in addition to these ducts or passages an additional duct 25 passage to be fed from a separate gasolene conduit, and to provide a valve operating independently of the throttle for controlling the passage of gasolene through either of the gasolene supply passages, or to shut 30 them off altogether, thus making it possible to adjust the throttle to a certain angle for the passage of the different mixtures, and with the throttle thus set, to dilute or ricken the mixture delivered through all of the 35 ducts which are exposed, this dilution or enriching of the mixture being accomplished without changing the position of the throttle, that is, without exposing more of the ducts of the distributor, or shutting off any 40 of the ducts. With this construction, it is not necessary to use such a small drill for the ducts, as it is possible to restrict the flow of gasolene to the ducts, and thereby reduce the amount flowing therethrough to the 45 desired quantity. Thus, the amount of gasolene permitted to discharge from the ducts is controlled first,—by regulating the position of the throttle to open a more or less number of ducts, and second,—by the separate valve to control the amount of gasolene, which flows to supply the ducts. This additional valve may also be entirely closed when it is desired to completely stop the flow of gasolene and economize, in coasting.

Referring to the drawings: Figure 1 is a 55 plan view. Fig. 2 is a side elevation. Fig. 3 is a section on line x^3-x^3 , Fig. 1. Fig. 4 is a section on line x^4-x^4 , Fig. 1. Fig. 5 is a section on line x^5-x^5 , Fig. 6. Fig. 6 is a section on line x^6-x^6 , Fig. 4. Fig. 7 is a 60 plan view of the throttle.

1 designates an outer stationary cylindrical casing, within which is located the throttle, which consists of a revoluble cylindrical shell 2, having openings 3 and 4 diametrically opposite each other from the ports, and a central stationary cylindrical drum 5 formed with a diametrical passage 6, having straight walls 7, which are parallel to the line of travel of the mixture in moving 70 from the distributor 8 to the upper chamber 9 of the carbureter, as clearly shown in Fig. 3. The throttle valve 2 has a head 10 at one end only, the left hand end fitting in a groove 11 formed in the casing 1, and the 75 head 10 is secured to a thin hub 12 having a considerable diameter to give the necessary rigidity and formed on a shaft 13 journaled in the casing 1 and operated by a lever 14. The inner end 14^a of shaft 13 is journaled in the drum 5. The shell 2 operates in the annular space formed between the stationary drum 5 and casing 1, and the ports 3 and 4 therein are formed, as indicated in Fig. 7, each having a curved edge 15, which 80 is so proportioned as to give a quick opening for a relatively small movement of the valve at the initial opening movements and to decrease the rapidity of opening of the ducts of the distributor as the throttle is adjusted further, the curvature of said edge 85 increasing in degree from end to end of the shell for that purpose.

The distributor 8 is located below the throttle, and is provided with a series of 95 ducts 17, all of which communicate at the bottom with a horizontal channel 18, which receives gasolene from a passage 19. One of the ducts 17^a is always open by reason of the cutaway portion 20 in the throttle, as 100 clearly shown in Figs. 4 and 7. In addition to the ducts 17 and 17^a, I provide a special duct 21, which is also always open by reason of the opening 20. The duct 21 receives gasolene from an independent passage 22, 105 which is supplied from a conduit 23, see Fig. 6. The conduit 23 lies a short distance above the conduit 19, and is parallel there-

with, the conduit 19 being shown in dotted lines in Fig. 6 below a conduit 23. Both conduits 19 and 23 communicate with a vertical passage 24, in which is slidable a valve 25, the lower end of which is tapered as shown. This valve has a grooved end 26 which is engaged by a lever 27.

The discharge ends of the ducts 17 are slightly spaced apart from the periphery of the shell 2, say one-thirty-second of an inch, so as to prevent capillary action drawing the fuel up through said ducts when the throttle is closed; and the discharge ends of the ducts 17^a and 21 may extend above the level of the discharge ends of the ducts 17 so as to more readily discharge through the cut away portion 20.

The lower end of the vertical passage 24 communicates with the float chamber 28, as clearly shown in Fig. 5. As the particular construction of the float chamber and parts associated therewith does not form part of the present invention, description of the same is unnecessary.

25. Air is admitted to the distributing chamber 30 through an air inlet passage 31, and an adjusting screw 32 extends into the distributor chamber near the upper end thereof, and in line with the distributor passages 30 17^a and 21 and may be adjusted to control the amount of air admitted to these two passages alone.

The distributor 8 is spaced apart from the transverse walls of the distributor chamber 30 to form passages on both sides of the distributor, the advantage being that when the throttle valve 2 is so adjusted as to open both sides of said passages maximum suction on the distributor can occur, whereas when 40 the throttle valve is so adjusted as to close one of said passages the suction on the distributor will be much diminished because air will flow past the distributor only on one side thereof.

5. In practical operation, suction of the engine, to which the carbureter is connected, draws air through the inlet passage 31 past the fuel distributor 8 and through the opening 4, passage 6, opening 7 and upper chamber 9 to the engine cylinder. Assuming that an extra rich or dense mixture is desired, as when starting the engine into operation or to meet the requirements of an extra heavy load on the engine, the levers 55 14 and 27 will be adjusted by the operator to partly close the throttle valve and to fully open both conduits 19, 23 so that fuel will be sucked from said conduits through the distributor ducts 17, 17^a and 21 into the 60 air passing through the distributor chamber and thereby produce a relatively rich mixture. If a less dense mixture and greater volume of mixture are desired, the lever 14 will be operated to fully open the throttle 65 valve. If a still less dense mixture and

maximum volume are desired, the lever 27 will be operated to move the valve 25 to close the duct 23, and the denseness of the mixture may be still further diminished by moving the valve 25 to partly close the duct 19. When it is desired to admit only air to the engine cylinder, the valve 25 will be moved to entirely close the duct 19. Ordinarily the valve 25 will be adjusted to regulate the flow of fuel through the duct 19 for normal running conditions, and under such conditions the operator will move the lever 14 so as to simultaneously regulate the volume of mixture and the amount of fuel drawn from the distributor, and it is noted that the proportions of air and fuel will remain practically unchanged for the various degrees of opening of the throttle valve when the throttle valve only is adjusted. Thus it is seen that the volume of mixture and not the quality thereof is governed by movement of the throttle lever 14 and that the quality of the mixture as regards its density is governed by movement of the lever 27.

What I claim is:

1. In a carbureter, a distributor chamber, a fuel distributor in the distributor chamber having a series of ducts, a stationary drum provided with a diametrical passage therethrough in axial alinement with said ducts, and a rotative shell fitting the outside of the drum and provided with diametrically opposite openings designed to be brought into registration with the ends of the passage of the drum, the margin of one of said openings being designed to close over the upper ends of the ducts.

2. In a carbureter, a casing, a distributor therein, a throttle valve within the casing above the distributor comprising a revolvable cylindrical shell provided with ports, and a stationary member within said shell supported by the casing and provided with a mixture passage.

3. In a carbureter, a casing, a distributor therein, a throttle valve in said casing above the distributor and comprising a cylindrical shell, one end of which is closed, and the other open, the shell being provided with ports, and a stationary drum projecting into said shell and supported at one end by the casing, said drum being provided with a diametrical mixture passage.

4. In a carbureter, a casing provided with a cylindrical enlargement, a cylindrical throttle valve in said casing, a distributor below the throttle valve, the throttle valve comprising a shell with a closed end and an open end, a shaft rotatable in the casing, the shaft having a thin hub which extends into the closed end of the throttle and secures the same to the shaft, said throttle being provided with ports, and a stationary drum within said shell, said drum being support-

ed at one end by said casing, the other end of said drum being provided with a bearing for the inner end of said shaft.

5. In a carbureter, a casing, a distributor, a series of ducts, a passage for supplying gasolene to all of said ducts, said distributor having another duct, a passage for independently supplying gasolene to the latter duct only, and a single valve for controlling the flow of gasolene through both of said passages.

6. In a carbureter, a casing, a distributor therein provided with a series of ducts, the discharge mouths of which are in line and 15 provided with another duct, the discharge mouth of which is above said line, said distributor being provided with a passage for conducting gasolene to all said ducts, the distributor being also provided with another 20 duct and with a passage for conducting gasolene to the latter duct, the discharge mouth of the latter duct being also above the line of said series of ducts, a float chamber, both of said passages communicating with the 25 float chamber, and a valve for closing one or both of said passages.

7. In a carbureter, a casing, a distributor therein provided with a series of ducts, the discharge mouths of which are in line and 30 provided with another duct, the discharge mouth of which is above said line, said distributor being provided with a passage for conducting gasolene to all said ducts, the distributor being also provided with another 35 duct and with a passage for conducting gasolene to the latter duct, the discharge mouth of the latter duct being also above the line of said series of ducts, a float chamber, both of said passages communicating 40 with the float chamber, a valve for closing one or both of said passages, a throttle valve above said distributor and formed with a convex face with a port therein, the edge of which is adapted to be moved across one or more of the mouths of said ducts to open 45 or close the ducts, said port being formed to expose the two ducts of higher elevation when all of the other ducts are closed in the throttle.

50 8. In a carbureter, a casing, a distributor therein provided with a series of ducts, the discharge mouths of which are in line and provided with another duct, the discharge mouth of which is above said line said distributor being provided with a passage for conducting gasolene to all said ducts, the distributor being also provided with another duct and with a passage for conducting gasolene to the latter duct, the discharge mouth 55 of the latter duct being also above the line said series of ducts, a float chamber, both of said passages communicating with the float chamber, a valve for closing one or both of said passages, a throttle valve above said distributor and formed with a convex

face with a port therein, which is adapted to be moved across one or more of the mouths of said ducts to open or close the ducts, said port being formed to expose the two ducts of higher elevation when all of the other ducts are closed in the throttle, and an adjusting screw projecting into the casing toward the distributor and under the throttle valve and in line with the two ducts having mouths of higher elevation for 70 controlling the passage of air to said latter ducts.

9. In a carbureter, a distributor chamber, a fuel distributor in the distributor chamber having a series of ducts, a stationary drum 80 provided with a diametrical passage therethrough in axial alinement with said ducts, and a rotative shell fitting the outside of the drum and provided with diametrically opposite openings designed to be brought into 85 registration with the ends of the passage of the drum, one of said openings being wider at one end of the shell than at the other end and the margin of said opening being designed to close over the upper ends of the 90 ducts.

10. In a carbureter, a distributor chamber, a fuel distributor in the distributor chamber having a series of ducts, a stationary drum provided with a diametrical passage there- 95 through in axial alinement with said ducts, and a rotative shell fitting the outside of the drum and provided with diametrically opposite openings designed to be brought into registration with the ends of the passage of the drum, one edge of one of said openings extending aslant relative to the axis of the shell and the margin at said edge being designed to close over the upper ends of the 100 ducts when the shell is rotated for that purpose.

11. In a carbureter, a distributor chamber, a fuel distributor in the distributor chamber having a series of ducts, a stationary drum provided with a diametrical passage 110 therethrough in axial alinement with said ducts, and a rotative shell fitting the outside of the drum and provided with diametrically opposite openings designed to be brought into registration with the ends of the 115 passage of the drum, one edge of one of said openings being curved and the margin at said edge being designed to close over the upper ends of the ducts when the shell is rotated, and the degree of curvature of said 120 edge increasing from end to end of said opening.

12. In a carbureter, a distributor chamber, a fuel distributor in the distributor chamber having a series of ducts, a stationary drum 125 provided with a diametrical passage therethrough in axial alinement with said ducts, and a rotative shell fitting the outside of the drum and provided with diametrically opposite openings designed to be brought into 130

registration with the ends of the passage of the drum, the periphery of said shell being adapted to close over the upper ends of some of the ducts and being spaced slightly from 5 said ends.

13. In a carbureter, a distributer chamber, a fuel distributer in the distributer chamber having a series of ducts, a throttle to control some of said ducts, a conduit communicating with some of said ducts, another conduit communicating with another of said ducts, and a valve to control both of said conduits.

14. In a carbureter, a distributer chamber, a fuel distributer in the distributer chamber having a plurality of ducts, a throttle to control the passage of air through the distributer chamber, and a single valve to control the flow of fuel to one of said ducts 20 independent of the other ducts and to control said other ducts at one time.

15. In a carbureter, a distributer chamber, a fuel distributer in the distributer chamber having a row of ducts, a conduit communicating with one of said ducts, a second conduit communicating with the remaining ducts, means to separately control the flow of fuel to both conduits, and a throttle valve 25 rotatively mounted above the distributer and provided with an opening adapted to register with all of said ducts and provided with a peripheral cut-away portion adjacent said one duct, said throttle valve being adapted to close over the discharge ends of all of the ducts excepting said one duct when said valve is turned to move the opening away from the distributer.

16. In a carbureter, a distributer chamber,

a fuel distributer in the distributer chamber having a row of ducts, a conduit communicating with one of said ducts, a second conduit communicating with the remaining ducts, means to separately control the flow of fuel to both conduits, and a throttle valve 40 rotatively mounted above the distributer and provided with an opening adapted to register with all of said ducts and provided with a peripheral cut-away portion adjacent said one duct and communicating with said opening, and said throttle valve being adapted to close over the discharge ends of all of the ducts excepting said one duct when 45 said valve is turned to move the opening away from the distributer.

17. In combination, a distributer chamber, 50 an upper chamber in axial alinement with the distributer chamber, a cylindrical casing connecting said chambers to one another, a rotative shell fitting inside of said casing and provided with diametrically opposite openings 55 adapted to register with the adjacent ends of the chambers, a stationary drum fitting inside of the shell and provided with a passage therethrough in axial alinement with said chambers, and a distributer in the distributer chamber having ducts discharging 60 toward the passage, the ends of said ducts being close to the periphery of the shell.

In testimony whereof, I have hereunto set 70 my hand at Los Angeles, California, this 13th day of May, 1914.

HARRY A. MILLER.
